UNITED STATES PATENT OFFICE.

HORACE R. WHITTIER, OF PLYMOUTH, CONNECTICUT.

OVEN THERMOMETER.

Application filed February 15, 1924. Serial No. 693,101.

This invention relates to those thermometers which are more particularly designed to be fastened to the side walls, rather than the front walls or doors, of insulated electrically heated ovens, although, of course, they are adapted to be used in connection with ovens heated by other means, for indicating the temperature therein.

The object of the invention is to provide a side wall thermometer which is cheap to manufacture, simple to install, efficient in use, very easy to read, and through which gases and vapors cannot escape.

In the accompanying drawings Fig. 1 shows a side elevation of a thermometer which embodies the invention applied to the insulated side wall of an oven. Fig. 2 shows a section on the plane indicated by the dotted line 2—2 on Fig. 1. Fig. 3 is a section on the plane indicated by the dotted line 3—3 on Fig. 1. Fig. 4 is a view in elevation of the inner end of the device.

The device has a cylindrical shell 1 of sufficient length to extend through the wall 25 of the oven. This shell is preferably drawn to a cup shape from sheet metal so as to leave the inner end closed. Permanently attached to the open front end of the shell is a face plate 2. This attachment may be 30 accomplished by providing the front end of the shell with lugs 3 and passing these lugs through correspondingly shaped openings in the face plate and heading them over on the outside of the plate. The peripheral 35 wall at the inner end of the shell is threaded and turning on this is a nut 4. The shell is passed from the front through an opening which it closely fits until the face plate rests against the outside casing wall 5 of 40 the oven. A clamping plate 6 is placed on the inner end of the shell against the inside sheathing wall 7 of the oven and then the nut is screwed on and turned up so as to 45 tightly secure the parts in position and prevent leakage of gases and vapors through the oven wall about the shell.

Extending through the front plate and the rear closed end wall of the shell is a spindle 8. Fastened to the rear end of the 50 spindle back of the closed inner end wall of the shell is an arm 9. A curved strip 10 of bimetallic thermo-responsive metal has one end pivotally mounted on a stud 11 projecting from the closed inner wall of the shell and has its other end pivotally connected with the arm attached to the spindle,

so that any change in the shape of the thermostatic strip will through the arm impart a rotative movement to the spindle. A stop stud 12 is provided for limiting the contracting movement of the thermostatic strip. Fastened by screws 13 to the closed inner end of the shell in such manner as to protect the thermostatic strip is a guard cap 14. The end of this cap is provided with 60 openings 15 and its edge is located away from and does not abut against the shell, so that while it protects the strip from injury, it does not offer any material obstruction to the free circulation of heated air to and 65 about the strip.

Attached to the front end of the spindle is an arm 16. This arm extends radially from the spindle in front of but close to the outer surface of the face plate and its 75 swinging end has an angularly arranged tell-tale plate or disk 17 which is desirably coated with white enamel and has a contrasting index line 18.

The face plate which is segmental in outline has three outwardly projecting ears 19. The plate is attached to the shell so that the spindle passes through it near the axis of the segment and the tell-tale at the outer end of the arm on the spindle will travel on an arc near the curved edge of the segment, as the variations of temperature changes the positions of the parts. Fitted over the front of the face plate and held thereto by engagement with the ears 19 is a casing 20. 80 This casing is of segmental shape corresponding to the shape of the face plate and it encloses the pointer arm. In the curved edge of the casing is a thermometer-shaped slot 21 and the wall of the casing along the 85 edges of this slot is provided with graduations and temperature indicating numerals. 90

In the device as made the casing is stamped from sheet metal and is coated on the outside with white enamel, the graduations and numerals being shown thereon in black or colors contrasting with the white coating of the casing. As the temperature in the oven to which the device is applied changes the indicating or tell-tale disk on the end of the 100 pointer arm is carried up and down closely adjacent to the slot in the curved edge of the casing and as the casing is white and the slot shows black the position of the white disk with its indicating line is plainly visible 105 for a considerable distance away from the front of the oven. The device constructed as 110

described may be attached to the side wall of an oven rather than the front or to a swinging door so that it is out of the way and is not in position to be knocked and injured, and yet when attached to a side wall in this manner its indications are clearly seen. Substantially all of the parts of the structure are stamped or drawn to shape from sheet metal. No glass is necessary to protect and close in the openings. The indicating arm is protected by the casing and there is no communication or passage between the opening in the casing and back of the closed end of the shell, except for the passage of the spindle which is fitted sufficiently tight to prevent the escape of vapors, gases and odors from the oven through the device. The device is so clamped in place that there is no chance for gases and vapors to work into the insulating material between the outer casing and inner sheathing walls of the side wall. The action is very efficient for the thermo-responsive strip, while protected, is exposed to the full effect of the heated air in the oven.

The invention claimed is:

1. An oven thermometer comprising a cylindrical shell having a closed inner end and adapted to fit an opening in an oven wall, a face plate attached to the outer end of the shell, a nut threaded upon the inner end of the shell and adapted to clamp the parts to the oven wall, a spindle extending through the closed end of the shell and the face plate, a thermo-responsive strip connected with the inner end of the spindle and adapted to turn it as the temperature changes, an arm fastened to and extending radially from the outer end of the spindle, a tell-tale plate attached to and extending angularly from the free end of the arm, a casing attached to the face plate and enclosing said arm and tell-tale plate, said casing having a curved edge wall with graduations thereon and a slot adjacent the inside of which the tell-tale plate is movable.
2. An oven thermometer comprising a cylindrical shell having a closed inner end and

adapted to fit an opening in an oven wall, a face plate attached to the outer end of the shell and adapted to lie against the outer surface of the oven wall, a nut threaded upon the inner end of the shell and adapted to clamp the parts to the oven wall, a spindle extending through the closed end of the shell and the face plate, a thermo-responsive strip connected with the inner end of the spindle and adapted to turn it as the temperature changes, a protecting cap secured to the end of the shell over the thermo strip, an arm fastened to and extending radially from the outer end of the spindle, a tell-tale plate attached to and extending angularly from the free end of the arm, a casing attached to the face plate and enclosing said arm and tell-tale plate, said casing having a curved edge wall with graduations thereon and a slot adjacent the inside of which the tell-tale plate is movable.

3. An oven thermometer comprising a cylindrical shell having a closed inner end and adapted to fit an opening in an oven wall, a face plate attached to the outer end of the shell and adapted to lie against the outer surface of the oven wall, a clamping plate loose on the inner end of the shell and adapted to lie against the inner surface of the oven wall, a nut threaded upon the inner end of the shell and adapted to clamp the parts to the oven wall, a spindle extending through the closed end of the shell and the face plate, a thermo-responsive strip connected with the inner end of the spindle and adapted to turn it as the temperature changes, a protecting cap secured to the end of the shell over the thermo strip, an arm fastened to and extending radially from the outer end of the spindle, a tell-tale plate attached to and extending angularly from the free end of the arm, a casing attached to the face plate and enclosing said arm and tell-tale plate, said casing having a curved edge wall with graduations thereon and a slot adjacent the inside of which the tell-tale plate is movable.

HORACE R. WHITTIER.
